Specification of Letters Patent.

Patented July 7, 1914.

Application filed December 11, 1913. Serial No. 805,949.

To all whom it may concern:

Be it known that I, DON LYMAN, a citizen of the United States, and resident of Twin Falls, in the county of Twin Falls and State of Idaho, have invented an Improvement in Life-Preservers, of which the following is a specification.

My present invention relates to life saving apparatus and more particularly to a suit to be worn by those in the water either able or unable to swim and adapted to permit of unobstructed use of the limbs of the wearer and of his eyes, nose and mouth and to exclude water from his person and protect him from floating obstacles and wreckage.

In carrying out my invention I provide a suit including a body portion to which leg and arm coverings with appendant feet and hand coverings are attached and to which is also attached a hood portion having a facial opening at the front thereof, the entire suit being formed of a suitable water excluding material and flexible throughout and the body having a front opening through which extends a flexible tubular lining through which the suit may be entered, this lining being subsequently drawn together and tied and thrust within the front of the suit, the lapped edges of the front opening of the body portion being subsequently fastened.

In the accompanying drawings which illustrate my invention, Figure 1 is a front elevation; Fig. 2 is a side elevation; Fig. 3 is a central vertical section with the lower leg portions broken away; Fig. 4 is a horizontal section taken substantially on line 4-4 of Fig. 3, and Fig. 5 is a perspective view illustrating the front of the body opened and the lining extended and opened for entering the suit.

Referring now to these figures, A indicates the body portion, provided with a front opening *a* extending from a point somewhat above the waist-line to a point somewhat below the neck and having lapping edges provided with relatively engaging fastening members as indicated at *a'* for securing the same together to close the opening. As will be seen particularly in Figs. 1 and 5, the lower front portion of the body A is of increased proportions to provide a fullness for facilitating the entrance to and exit from the garment, this fullness being taken up after entrance of the wearer

in the form of a plait indicated at A', the lapping portions of which are provided with relatively engaging fastening members indicated at *a'*. The body A is made to fit loosely upon the body of the wearer and from its lower end depend leg portions B at the lower ends of which are feet B'. From the upper side portions of the body depend the arm coverings or sleeves C at the lower ends of which are hand-coverings or gloves C' and it is to be understood that it is within the province of the present invention to form the legs, feet, sleeves and gloves or hand-coverings either by weaving the same integral with the body A or forming the same in separate parts to be attached to one another and to the body by seams adapted either to exclude water due to their particular formation or to be rendered so by the application of suitable water excluding cement or rubber composition, it being important in each instance that the natural flexibility of the material be retained so far as possible in order that free movements of the wearer will not be impaired or obstructed. To the neck of the body portion A is adapted the hood or head-covering D, having at its front a face opening *d* which is preferably of a circular form as particularly shown in Fig. 1 and of such proportions as that its edge will lie against the forehead, cheeks and chin of the wearer and thus expose the eyes, nose and mouth.

Within the garment are disposed a plurality of flexible air containers to be suitably inflated, one of these air containers being shown at E and extending entirely around the garment below the lower end of the front opening *a*. Another container F extends upwardly along and entirely across the rear portion of the body A and a pair of similarly shaped containers G and G' extend upwardly along opposite sides of the front of the body A, one upon each side of its opening *a*. Still another container extends upwardly around the rear portion of the hood or head-covering D and indicated at H, it being noted that each of these containers is formed by an inner supplemental piece I, the edges of which are suitably secured to the inner surface of the garment so as to form a pocket to receive a flexible, inflatable inner member I' as particularly shown in Figs. 3 and 4.

Secured at its inner end around the front

opening *a* is a flexible tubular lining *K* which may be extended outwardly as shown in Fig. 5 when entrance into or exit from the suit or garment is desired, it being noted from Fig. 3 that the outer end of this tubular flexible lining *K* is drawn together and securely tied by a flexible tie member *k* after entrance into the suit and is covered and protected by the lapped and fastened side edges of the opening *a* when the suit or garment is in use.

The several air containers *E*, *F*, *G*, *G'* and *H* are provided with inflating tubes *e*, *f*, *g*, *g'* and *h* respectively whereby they may be inflated to a desired point after entrance into the suit either by the wearer or by a suitable pump used exteriorly thereon, it being of course within the province of the invention to either close these tubes by tying or to provide the same with the well-known air valves as used in connection with the valve tubes of inflatable tires, or what are known as pillow valves. Preferably the several containers are inflated to such an extent as to cause them to press closely against the wearer in order to assist in preventing the communication of the chill of cold water to him as well as to protect his body from the shock of floating obstacles and wreckage, in addition to which the air container *H* within the hood or head-covering *D* is inflated to such an extent as to draw the edge of the face opening *d* snugly against the face of the wearer to prevent the entrance of moisture in rough water.

A life preserving garment or suit of the character described will effectively protect and keep the wearer afloat, will permit of the unobstructed use of his body and limbs as well as permit him to breathe freely and see clearly. It is possible for the wearer to maintain himself either in a vertical or horizontal position in water and to escape the deadly chill of intense cold. It will also be noted that a life preserving suit or garment of the present structure may be entered and properly secured by the user, without aid or assistance from others, and when so secured, will serve to retain the heat of the user's body to obviate suffering in cold weather. It is to be also noted that one or more pockets indicated at *M* may be provided in the garment or suit for the reception of certain necessary articles including a bottle of fresh water, a small supply of condensed food and a flashlight.

I claim:

1. A life preserving garment of the character described comprising a body portion having a front opening provided with lapped edges and with fastening members for securing the edges together in closed

position, a hood projecting upwardly from the body, legs and sleeves depending from the lower and side portions of the body and respectively provided with foot and hand-coverings, and a flexible lining of tubular form secured at its inner end around the front opening of the body and adapted to be extended through said opening when the lapped edges are disconnected, for the purpose described.

2. A life preserving garment of the character described comprising a body portion having a front opening provided with lapped edges and with fastening members for securing the edges together in crossed position, a hood projecting upwardly from the body, legs and sleeves depending from the lower and side portions of the body and respectively provided with foot and hand-coverings, a flexible lining of tubular form secured at its inner end around the front opening of the body and adapted to be extended through said opening when the lapped edges are disconnected, and a flexible tie member for closing the outer end of the tubular lining, all for the purpose described.

3. A life preserving garment of the character described comprising a body portion and a hood, sleeves and leg portions extending from the body portion, the body portion having a front opening and a substantially increased fullness adjacent its lower end and the lower end of the opening, fastening members for securing the edges of the opening in lapped relation, and fastening members secured to the lower front of the body portion whereby the fullness may be taken up in the form of a plait when the garment is in use.

4. A life preserving garment of the character described, comprising a body portion having a front opening provided with lapped edges and with fastening members for securing the edges together in closed position, a hood projecting upwardly from the body, legs and sleeves depending from the lower and side portions of the body and respectively provided with foot and hand-coverings, a flexible tubular lining secured at its inner end around the front opening of the body and adapted to be extended through the body opening when the lapped edges thereof are disconnected, and a plurality of air containers, certain of which are arranged in the hood and in the body of the garment in order to protect the wearer in water and provide the necessary buoyancy.

DON LYMAN.
